his Atty.

UNITED STATES PATENT OFFICE.

HENRY A. WILLIAMSON, OF CHICAGO, ILLINOIS.

GARBAGE-PRESS.

1,187,118.

Specification of Letters Patent. Patented June 13, 1916.

Application filed November 10, 1915. Serial No. 60,634.

To all whom it may concern:

Be it known that I, HENRY A. WILLIAMSON, a citizen of the United States, and a resident of Chicago, county of Cook, and State of Illinois, have invented certain new and useful Improvements in Garbage-Presses, of which the following is declared to be a full, clear, and exact description.

This invention relates to presses for use in compressing fruits, vegetables and other food commodities, garbage and many other substances, and its principal object is to provide a simple, practical and efficient press, which may be supported on a wall or other vertical surface, and having a plunger carried by a swinging support, which may be moved from a position, when the plunger is maintained in coaxial alinement with the compression chamber, to one at the side thereof, whereby access may be readily had to said chamber for the purpose of depositing material into the same.

Another object is to provide hinged vertical walls for the compression chamber, whereby the compressed material may be readily removed therefrom.

Another object is to provide means for draining away water or other liquid, which is forced out of the compressed material.

Other objects and advantages will readily appear in the course of this specification, and with said objects and advantages in view this invention consists in the several novel features hereinafter described and claimed.

The invention is clearly illustrated in the accompanying drawing, in which:

Figure 1, is a front elevation of a press embodying a simple form of the present invention; Fig. 2, is a vertical section taken on line 2—2 of Fig. 1; Fig. 3, is a plan of the press, and Fig. 4, is a horizontal section taken on line 4—4 of Fig. 1.

In the embodiment of the invention illustrated in said drawing, 10, designates a supporting frame, comprising a vertical base plate 11, having screw or bolt holes 12, for the reception of the screws or bolts which fasten the device to its support. Extending forward from said plate 11, is a table or shelf 13, which has a raised portion 14, near its forward end, which forms one end of the compression chamber; the upper face of the

table, surrounding said raised portion, is formed with a trough 15, at the forward end 55 of which is a spout through which liquid may drain from the device. Surrounding and extending up from said raised portion 14, are the two sections 16, 16, of the vertical wall of the compression chamber, which wall 60 sections are pivotally connected with the frame on vertical pivots. In the form shown, the compression chamber wall is in the form of a cylinder, and the raised portion 14, of the table fits against the inner 65 face of the cylindrical wall at its lower end. Each semicylindrical wall section 16, has upper and lower rearwardly extending lugs or ears, 17, secured thereto or cast integral therewith, the lower lugs or ears resting on 70 the table 13, and supporting the wall section; vertical pivot pins 18, extend through a forwardly projecting bracket 19, of the frame, through the ears 17, and into the table 13, where they may be secured in place, 75 as for instance by being threaded on their lower ends and screwed into threaded holes in the upper side of the table. To the front of one semicylindrical wall section 16, are pivotally secured latches 20, 20, which are 80 arranged to hook over lugs or hooks 20^a, 20^a, which project out from the front of the other semicylindrical wall section. Access may be had to the compression chamber by unfastening the latches from the hooks and 85 swinging the semicylindrical wall sections back as shown in Fig. 4, and this is done when the contents are to be removed from the compression chamber.

Above the compression chamber is a plunger supporting arm 21, in the forward end of which is mounted the screw threaded stem 22, of a plunger 23, which fits the bore of the cylinder and is movable up and down therein. On the upper end of said screw threaded stem 22, is a hand wheel, 24, for use in turning the stem, and if desired said hand wheel may have an upstanding handle 24^a by means of which the wheel may be turned. The arm 21, is pivotally mounted between 90 forwardly projecting brackets 25, 26, formed on the plate 11, and for securing the arm 21, to the brackets 25, 26, I employ two pins 27, 27, which are inserted through registering holes in the brackets and arm, there being 95 one pin at each side of the middle of the

brackets. When both pins 27, are in place the arm is held in position with the plunger in coaxial alinement with the cylindrical compression chamber, but by withdrawing 5 either pin the arm, together with the plunger (when withdrawn from the compression chamber) may be swung to one side of the same, thereby uncovering the chamber so that material to be compressed may be inserted therein. The retracted position of the arm and plunger is shown in dotted lines 10 in Fig. 1. An abutment member 28, is formed on the plate or arm for taking up the strain when the plunger is screwed down 15 hard; said abutment member is here shown as formed on the base plate 11, and projecting forward over the arm, 21.

In use the two semicylindrical wall sections of the compression chamber are secured 20 together by the latches at the front thereof, the plunger raised out of the chamber, one of the pins 27, removed and the arm and plunger swung to one side, thus uncovering the chamber. Material to be compressed 25 may be deposited in the compression chamber, and, if the press is used as a garbage press, it may be supported over a kitchen sink so that the liquid discharged from the compression chamber may drain into the 30 sink. After the compression chamber has been filled or partially filled, the plunger carrying arm 21, is swung over the chamber and the removed pin inserted in the registering perforations in the brackets 25, 26, and 35 arm 21. The hand wheel 24, may now be turned in the proper direction to lower the stem and plunger, and the latter thereby forced down upon the material in the compression chamber, thus compressing it into 40 a compact mass, and at the same time forcing the greater part of the water or other liquid contained therein out through the perforations in the cylindrical wall, from which it runs into the trough in the table, and 45 finally drains out through the spout.

When it is desired to remove the compressed material, the two semicylindrical wall sections are unlatched from each other and swung back, thus exposing the contents, 50 which may be lifted off the raised part of the table. If desired a plate 30 (see Fig. 2) may be placed upon said raised part of the table to receive the contents of the compression chamber, and said plate will furnish 55 convenient means for carrying the compressed material away from the press.

Obviously, fruit, vegetables or other food commodities may be pressed in a press embodying the present invention and the juices, 60 pressed out of the food may be gathered in a suitable vessel supported below the spout.

Various alterations and modifications of this press may be made without departing from the spirit of this invention; I desire, 65 therefore, not to limit myself to the exact

form of construction shown and described but intend in the following claims to point out all of the invention disclosed herein.

I claim as new and desire to secure by Letters Patent:

1. A press of the class described, comprising in combination, a supporting frame formed with an outstanding table having a raised portion which forms an end wall of a compression chamber, a divided side wall surrounding and extending upward from said raised portion, the sections of said wall being movable away from each other for access to the compression chamber, a vertically reciprocatory plunger movable into and out of said compression chamber, plunger 75 actuating means, and a horizontally swinging support for said plunger, pivotally mounted on said supporting frame, said swinging support being capable of movement toward either side of the supporting frame, whereby the plunger may be bodily shifted out of co-axial alinement with the compression chamber.

2. A press of the class described, comprising in combination, a supporting frame formed with an outstanding table having an annular groove in its upper face and a spout leading therefrom, a compression chamber side wall, extending upward from said table, 90 a reciprocatory plunger movable into and out of said compression chamber, a screw threaded stem carrying said plunger, in which said stem is threaded, and an arm, pivotally supported on said frame by two 95 pivot pins, there being one pin at each side of the frame, whereby, when either pivot pin is withdrawn, the arm and therewith the plunger may be swung to one side of the frame to afford access to the compression 100 chamber.

3. A press of the class described, comprising in combination, a supporting frame formed with an outstanding table, an upright divided cylindrical wall extending up 110 therefrom and inclosing a compression chamber, the two sections of said divided wall being pivotally secured to said supporting frame and having latches for securing them together, a vertically reciprocatory 115 plunger movable into and out of said compression chamber, a screw threaded stem carrying said plunger, a supporting arm in which said stem is threaded, and a pivotal connection between said arm and frame upon 120 which said arm, and therewith the stem and plunger, may be swung from the compression chamber, and an abutment member extending out from said frame above said arm, against which said arm abuts when the 125 plunger is screwed down against the contents of the compression chamber.

4. A press of the class described, comprising in combination, a supporting frame formed with an outstanding table, having 130

- a raised portion, a trough surrounding said raised portion and a spout leading from said trough, an upright divided, cylindrical wall surrounding said raised portion and 5 extending up therefrom, the two sections of which are pivotally supported on said frame on vertical pivots and capable of being swung apart to expose the interior thereof, a vertically reciprocatory plunger movable 10 into and out of the chamber formed by said cylindrical wall, a screw threaded stem carrying said plunger, a horizontally movable arm in which said stem is threaded, mounted on said frame on a vertical pivot whereby 15 said arm and therewith the stem and plunger may be swung away from the cylindrical wall, means for stationarily securing said arm in place with the plunger in co-axial alinement with the chamber of said cylindrical wall and an abutment member extending 20 out from said frame above said arm, against which said arm abuts when the plunger is screwed down against the contents of the compression chamber.
- 25 5. A press of the class described, comprising in combination, a supporting frame formed with an outstanding table having a raised portion, a trough surrounding said raised portion and a spout leading therefrom, a perforated cylindrical wall surrounding said raised portion and extending up therefrom and movably supported on said frame, a plunger movable into and out of the chamber formed by said cylindrical wall, plunger actuating means including a 30 horizontally movable arm pivoted on said frame and capable of being swung, together with the plunger, to one side of the cylinder, and an abutment member extending out
- from said frame above said arm, against 40 which said arm abuts when the plunger is screwed down against the contents of the compression chamber.
6. A press of the class described, comprising in combination, a supporting frame, 45 formed with an outstanding table, a divided cylindrical wall extending up therefrom and movably supported on said frame, a plunger movable into and out of the chamber formed by said cylindrical wall, a screw threaded 50 stem carrying said plunger, a hand wheel on said stem, a horizontally movable arm in which said stem is threaded, and two vertically extending retractable pivot pins, one at each side of the frame, pivotally connecting 55 said arm with the frame at two places, whereby said arm may be swung away from its fixed position in either direction by withdrawing one pivot pin.
7. A press of the class described, comprising in combination, a supporting frame formed with an outstanding table, a divided, perforated cylindrical wall extending up therefrom, each section of said wall having rearwardly extending ears pivoted to said 60 frame on vertical pivot pins, means for securing the two sections of said wall together, a plunger movable into and out of the chamber formed by said cylindrical wall, a screw threaded stem carrying said plunger, a horizontally movable arm in which said plunger is threaded, said arm being pivotally secured to said frame by two vertically extending 65 retractable pivot pins, and an abutment member for said arm against which said arm 70 abuts when the plunger is screwed down against the contents of the chamber.

HENRY A. WILLIAMSON.
